UNITED STATES PATENT OFFICE.

SAMUEL HOSKEN, OF JOHANNESBURG, TRANSVAAL, SOUTH AFRICA.

FURNACE FOR HEATING ROCK DRILLS AND ROCK-DRILL STEEL.

Application filed January 12, 1924. Serial No. 685,848.

To all whom it may concern:

Be it known that I, SAMUEL HOSKEN, a subject of the King of Great Britain, and resident of Johannesburg, Transvaal Province, Union of South Africa, have invented a certain new and useful Improvement in Furnaces for Heating Rock Drills and Rock-Drill Steel, of which the following is a specification.

10 This invention has reference to furnaces particularly designed for and especially applicable for heating bars of steel which are to be forged or formed into rock-drills, or rock-drilling machine bits, and for heating such drills, bits or the like preparatory to re-sharpening the same and also for heating such drills or bits for the purpose of hardening the cutting ends and shanks thereof.

20 One object of the present invention is to devise an electrical furnace in which the drill or drill steel can be heated gradually, or in stages, to any desired and predetermined maximum temperature.

25 A further object is to ensure that the drill, bit, etcetera, shall pass continuously through all the stages of the heating process in a predetermined period or length of time.

30 A still further object of the invention is to ensure that the drill or drill steel shall not be withdrawn from the furnace during its passage therethrough.

According to the invention the furnace is constructed in or divided into any desired and suitable number of sections, arranged 35 in such a manner that the drills, bits, etcetera, in the heating process, will travel through the section of the furnace of lowest temperature and continue without stopping through the succeeding sections of gradually rising or higher temperature into the last section, which is heated to the desired maximum temperature.

35 The means which is provided for carrying or passing the drills, bits, etcetera, through the several sections of the furnace are designed so that the passage of the drills through the furnace takes place during the predetermined period of time necessary to raise the drills, etcetera, gradually to the desired maximum temperature, and preferably so that the temperature of the drills is raised to the temperature of each section

of the furnace in their passage through such section.

55 Preferably adjustable means are provided which prevent withdrawal of the drill or steel during its passage through the furnace.

The invention will be fully described with the aid of the accompanying drawings wherein, by way of example, two embodiments of the invention are illustrated.

In the drawings,

Fig. 1 is a side elevation of one embodiment of the invention, with the means which carry the drills through the furnace removed.

65 Fig. 2 is an end elevation of Fig. 1 with certain of the carrying means omitted.

70 Fig. 3 is a plan of Fig. 1 also with portions of the carrying means omitted.

75 Figs. 4, 5 and 6 are side elevation, end elevation and plan views respectively of certain portions of the carrying means.

Fig. 7 is a detail view of a portion of the heating chamber of the furnace illustrating 75 a means for preventing the withdrawal of the drills from said chamber at any point intermediate the entrance and exit.

80 Fig. 8 is a side elevation of the other embodiment of the invention with a portion of the means for carrying the drills omitted, and

85 Fig. 9 is a half-sectional end elevation of the furnace illustrated in Fig. 8.

Referring to the embodiment of the invention illustrated in Figs. 1 to 6 of the drawings, the furnace is so constructed and arranged that the drills are passed or carried through it in a vertical or upright position. In this form of the invention I provide a suitable supporting framework 1 which carries the two plates 2, 3, which form a divided table upon which is erected and secured the several sections of the heating chamber or furnace proper. Each section of the arched heating chamber 4, as shown, is formed by the two side bricks or blocks 5, 6, and the top brick or block 7, all of appropriate shape and made of any suitable refractory material. The side bricks 5, 6, 90 form between their adjacent inner sides an opening which coincides with the slot or opening 8 between the inner edges of the plates 2, 3, of the table.

Each section of the heating chamber 4 is enclosed in a metal or other suitable casing comprising the two parts 9, 10, which are connected together at the top, as indicated 5 at 11, and are hinged at the sides, as indicated at 12 and 13, to the vertical plates 14, 15, which are fixed to the top of the table and extend the full length of the furnace at the outside of the side bricks 5, 6, of all the 10 sections of the furnace. The space between the casing 9, 10, and the bricks 5, 6, 7, may be filled with any suitable heat non-conducting material.

For the purpose of heating the furnace 15 electrically heating elements 16, 17, are shown arranged upon the side bricks or blocks 5, 6, inside the chamber 4, at opposite sides of the opening 8, said elements being electrically connected by suitable conductors 18, 19, 20, 21, 22.

The number of sections comprised in the furnace structure and consequently the aggregate length of the heating chambers provided by the said sections is designed to accommodate 25 the number of drills, which it is required to heat in a given period of time, in such a way that the drills attain the temperature of each section before passing into the next succeeding section of higher 30 temperature. The temperature gradient or gradually rising temperature of the furnace is obtained by heating each successive section a greater temperature than the preceding section from the entrance to the exit.

35 The means shown for carrying or passing the drills, etcetera, through the furnace include a framework 23 connected to the framework 1 and to the part 2 of the table, which framework 23 supports two oval endless tracks or rails 24, 25, one side of each of which tracks is arranged beneath the furnace slightly at one side of the opening 8 into the heating chamber 4. The drills 26 are attached to and carried through the furnace by an endless chain-like structure including links 27 to which are attached the carriers 28 which are provided with grooved wheels or rollers 29, 30—see Figs. 2 to 6—which run on the rails or tracks 24, 25, respectively. Each of the carriers 28 is provided at the upper end with means for attaching thereto the drill 26. The means shown for accomplishing this includes the formation of a recess 31 to take the stem of 50 the drill 26 and a screw 32 which, when screwed in one direction secures the drill in said recess 31, and in the reverse direction, disconnects the drill and allows it to be removed from the carrier 28. The carrier 28 is shown provided with two rests 33, 34, which are recessed to take the stem of the 55 drill 26, as shown in Fig. 2, and operate to steady the drill 26 and ensure its proper alignment as it is being carried through the furnace.

The means for driving the carrier chain includes the provision of a roller 35 for each carrier 28. The rollers 35 are shown mounted on the pins 36 which connect the ends of the links 27 of the chain. A shaft 37 is provided which runs in bearings 38, 39, and at its upper end, carries a sprocket wheel 40 which engages with the rollers 35 and so drives the carrier chain. For driving the shaft 37 a worm wheel 41 is mounted thereon which is driven by a worm 42, which is in turn driven by a worm wheel 43 off the worm 44 driven by the motor 45.

To ensure the drills being placed at the correct height in the carriers 28 to pass through the heating chamber 4, a gauge is provided comprising a plate 46 fixed to the frame 23. In attaching the drills 26 to the carriers 28 they are placed in the recesses 31 and rests 33, 34, and held against the underside of the gauge plate 46 while being secured to the carriers by the screws 32.

The furnace is designed to prevent the withdrawal of the drills in their passage therethrough. This object is attained by making width of the opening 8 at the bottom of the heating chamber 4 of such a width that the head or enlarged cutting end of the drill is unable to pass therethrough. If it be desired to make provision for the heating of smaller drills, the heads of which would pass through the opening 8 then this may be effected by providing means for altering the width of the opening. Such a means is illustrated in Fig. 7 in which a pair of eccentrically mounted rods 47, 48, are mounted in brackets 49, 50, and have levers 51, 52, fixed on their outer ends for placing and retaining the eccentric rods 47, 48, in the requisite positions to give the desired width of opening between them. The levers 51, 52 are provided with catches which co-operate with notched quadrants 53, 54, for retaining the said levers in position after the adjustment of the eccentric rods 47, 48.

In the embodiment of the invention illustrated in Figs. 8 and 9, the furnace is so arranged that the drills are passed through it whilst being supported and carried in a horizontal position. In this form the furnace is constructed to provide the central heating chamber 55, said chamber being formed between the bricks or blocks 56 arranged in and carried by the upper portion 57 of the framework and the blocks or bricks 58 arranged in the lower casing 59 which is supported by a pedestal 60. The ends of the framing of the upper portion of the furnace are carried by a suitable framework or supports 61.

The furnace is provided at both sides with openings 62, 63, leading into the heating chamber 55 so that two rows of drills can be heated simultaneously, two of the carrying

means being provided, one at either side of the furnace. 62^a, 63^a, are the electrical heating elements.

The driving arrangements for the carrying means in this construction is the same for both sides of the furnace and includes two horizontal shafts 64, 65, through one of which the motion may be imparted to the carrying means. These shafts run in intermediate and end bearings 66, 67, respectively, the intermediate bearings being carried by the pedestal 60, and the end bearings by separate pedestals 68. On each of the shafts 64, 65, at both sides of the furnace 10 there are mounted two sprocket wheels 69, 70.

The carrying means comprises, for each side of the furnace, a pair of endless chains. One chain engages with the two sprocket 20 wheels 69 nearest the side of the furnace, and the other with the two sprocket wheels 70, on the outer ends of the shafts 64, 65. The links of the chains are constructed to form the rests or carriers 71 for the drills 72. The two chains are connected by means of rods 73 on the outer ends of which there are mounted rollers 74, which are engaged by the teeth of the sprocket wheels to operate the chains to convey the drills through the 30 furnace. Both ends of the rods 73 are connected by means of smaller links 75 to impart the requisite rigidity to the carrier structure.

76 are two rails arranged at either side 35 of the furnace and supported by the framework 77, in front of the openings 62, 63, through which the drills 72 project into the heating chamber 55. On these rails 76 the rollers 74 of the carrier structure travel as 40 they convey the drills through the furnace. This ensures the drills being maintained in the correct horizontal or substantially horizontal position as they pass successively through the sections of the furnace of varying 45 temperature gradually to attain the maximum temperature in the predetermined period of time, which will depend upon the nature of the steel to be heated.

If desired means may be provided for 50 rotating the drill, etcetera, as it is passing through the heating chamber 55. As shown in connection with Fig. 8, the rotation of the drill may be effected by providing the drill carrier 71 with say two rollers 78, one at 55 either side of the rest 71, which rollers will be driven by frictional contact with the rollers 74, and by contact with the drill 72—which will lie between them—rotate the latter.

60 In this embodiment of the invention the gauge or loading plate 79, which is in the form of a vertical plate, is fixed to the framework and aligned to the centre of the heating chamber 55. As in the previously 65 described furnace the drills 72 are placed

in the carriers or rests 71 and pushed up to the gauge or loading plate 79, and are moved by the conveying means into and through the furnace, passing through the various sections of gradually rising temperature, and may be removed from the carrying means after they have passed out of the furnace or be allowed to fall out of the rests 71 as the latter pass around the sprocket wheels at the exit end of the furnace. To ensure that the drills shall only be removed from the carrying means after they have passed completely through the furnace, the bricks or blocks 56, 58 are formed with projections 80 which are arranged at such a distance apart that ordinarily the head of the drill cannot pass out of the furnace between said projections. If, however, it be desired to heat drills having heads of such a size as will pass between the projections 80, means similar to that illustrated in Fig. 7 may be employed to prevent the drills being withdrawn from the furnace during their passage therethrough.

The furnace according to this invention 90 is capable of heating rock drills or drill steels of any different ordinary lengths.

A furnace constructed for the electrical heating of drills, as hereinbefore described, can be used in the underground workings 95 of mines as there are no objectionable or deleterious fumes given off as is the case with furnaces in which fuel is consumed. Any suitable electrical control means may be used for maintaining the desired temperature in the various sections or zones of the furnace, and particularly the maximum or final temperature, according to the grade or class of steel being heated, thus obviating the possibility of overheating or burning of 100 the steel.

The predetermined time period necessary for the heating of the drills can be set and automatically controlled and can be that best suited to the nature of the steel to be heated. By the adoption of the furnace, once the drills have been placed in the conveying means, and in the case of the vertical type of furnace, fixed thereto, all handling is obviated until the drills reach the correct predetermined temperature and pass out of the furnace, and the furnace can be supervised by unskilled labour. The heating of the drills is uniform, and a high efficiency is attained as a result of the conservation of the heat by the construction adopted for the heating chamber. Further, the heating elements, as well as other parts of the furnace, can be easily replaced from time to time as required.

In order to obtain the best results with a furnace constructed as above described, it will be necessary first to determine the period of time that it is necessary and desirable to take in heating the drills, or raising 130

them to the desired maximum temperature. This will depend on the carbon content of the steel and other physical properties thereof, and the speed at which the conveying means carries the drills through the furnace is then adjusted or set to ensure that the steel or drill shall be carried through the furnace in such period of time.

What I claim as my invention and desire 10 to protect by Letters Patent is:—

1. An electrical furnace for heating rock-drills and rock drill steel, comprising a plurality of independently heated sections providing a continuous heating chamber of 15 different gradually rising temperatures from one end of the furnace to the other, in combination with mechanical means for continuously conveying the drills or drill steels which are to be heated through said heating 20 chamber, and means for preventing the withdrawal of the drills or drill steels from the furnace during their passage therethrough, as set forth.

2. An electrical furnace for heating rock-drills and rock drill steel, comprising a plurality of independently heated sections providing a continuous heating chamber of different gradually rising temperatures from one end of the furnace to the other, in combination with mechanical means for continuously conveying the drills or drill steels which are to be heated through said heating chamber, and adjustable means for preventing the withdrawal of the drills or 30 drill steels from the furnace during their passage therethrough, as set forth.

3. An electrical furnace for heating rock-drills and rock drill steel, comprising a plurality of independently heated sections providing a continuous heating chamber of different gradually rising temperatures from one end of the furnace to the other, in combination with mechanical means in the form of an endless chain-like structure for continuously conveying the drills or drill steels which are to be heated through said heating chamber, and a guage engaging with that end of the steel which is to be heated to ensure the drills or drill steels being placed 45 in the conveying means in the correct position to enter the heating chamber, as set forth.

4. An electrical furnace for heating rock-drills and rock drill steel, comprising a plurality of independently heated sections providing a continuous heating chamber of different gradually rising temperatures from one end of the furnace to the other, in combination with mechanical means for continuously conveying the drills or drill steels which are to be heated through said heating chamber, and means for preventing the withdrawal of the drills or drill steels from the furnace during their passage therethrough, 60 the mechanical means for conveying the

drills being in the form of a chain-like structure including carriers for the drills or steels, said carriers having recesses in which the drills or drill steels are placed and carried, links connecting said carriers, and a 70 pair of rollers for each carrier upon which said carriers are mounted, rails upon which said rollers are adapted to travel and driving means for the chain-like structure, said driving means including rollers mounted 75 on the carriers and a driving sprocket wheel adapted to engage said rollers to move the chain-like structure as set forth.

5. An electrical furnace for heating rock-drills and rock drill steel, comprising a plurality of independently heated sections providing a continuous heating chamber of different gradually rising temperatures from one end of the furnace to the other, in combination with mechanical means for continuously conveying the drills or drill steels which are to be heated through said heating chamber, means for preventing the withdrawal of the drills or drill steels from the furnace during their passage therethrough, 80 and means for rotating the drills or drill steels during their passage through the chamber, the mechanical means for conveying the drills or drill steels being in the form of a chain-like structure including carriers for the drills or steels, said carriers having recesses in which the drills or steels are placed and carried, links connecting said carriers, a pair of rollers for each carrier upon which said carriers are mounted, rails 85 upon which said rollers are adapted to travel, and driving means for the chain-like structure, said driving means including rollers mounted on the carriers and a driving sprocket wheel adapted to engage said rollers to move the chain-like structure, and the means for rotating the drills or drill steels during their passage through the chamber being in the form of rollers mounted upon the carriers and running in contact with the first-mentioned rollers and the drills or drill steels, as set forth.

6. A furnace of the nature indicated comprising a plurality of sections providing a continuous heating chamber of different gradually rising temperatures in combination with means for conveying the steel articles which are to be heated through said heating chamber and means for varying the width of the opening into the heating chamber to prevent withdrawal of the steel articles during their passage through the heating chamber, as set forth.

7. A furnace of the nature indicated comprising a plurality of sections providing a continuous heating chamber of different gradually rising temperatures, in combination with means for conveying the steel articles which are to be heated through said heating chamber and means for varying the

width of the opening into the heating chamber to prevent withdrawal of the steel articles during their passage through the heating chamber, said means including eccentrically mounted rods and levers for rotating said rods, as set forth.

In testimony whereof I have signed my

name to this specification in the presence of two subscribing witnesses:—
